UNITED STATES PATENT OFFICE

2,403,795

HIGH-FREQUENCY APPARATUS

William C. Hahn, Scotia, N. Y., assignor to General Electric Company, a corporation of New York

Application April 26, 1941, Serial No. 390,527

11 Claims. (Cl. 315—6)

1

The present invention relates to ultra high frequency apparatus utilizing the principles of velocity modulation and is considered useful in connection with high frequency oscillators, amplifiers, detectors, etc.

It is a primary object of the invention to provide ultra high frequency apparatus which is capable of realizing high power output and which is characterized by a high degree of stability and reliability in operation. In this connection an important feature of the invention consists in an arrangement in which a stream of charged particles (e. g. electrons) is caused to traverse an elongated chamber which is of continuously conductive character and which is subdivided into a number of intercommunicating and mutually coupled sections each of which is individually resonant at a common frequency. It is shown herein that by properly correlating the velocity of the charged particles to the longitudinal dimensions of the various chamber sections, useful high frequency energy conversion effects may be obtained by the mutual reaction of the charged particles and the structural elements of the chamber. For example, in accordance with one mode of use of the invention, the charged particles may be made to maintain the chamber in a condition of continuous resonant excitation such that it may be used as a fixed frequency oscillator for the generation of high frequency waves.

The features of the invention desired to be protected herein are pointed out with particularity in the appended claims. The invention itself, together with further objects and advantages thereof, may best be understood by reference to the following description taken in connection with the drawings, in which Fig. 1 is a longitudinal sectional view of a discharge apparatus suitably embodying the invention; Fig. 2 is a cross section taken on line 2—2 of Fig. 1; Fig. 3 represents a single section of the discharge chamber of Fig. 1, modified in a manner which assists in explaining the operation of the invention; Fig. 4 is a diagrammatic view representing the circuit analogue of the structure of Fig. 3; Fig. 5 is a fragmentary view also useful in explaining the invention; Fig. 6 is a longitudinal section of a modified embodiment of the invention; Fig. 7 is a cross section taken on line 7—7 of Fig. 6; Fig. 8 shows a further modification; Fig. 9 is a cross section taken on line 9—9 of Fig. 8; Fig. 10 illustrates a still further modification; Figs. 11 and 12 jointly illustrate a still further modification; and Fig. 13 shows the application of the invention to an amplifier.

Before proceeding to a detailed description of the invention it will be helpful to consider briefly some of the principles of velocity modulation as the same are set forth, for example, in my prior Patent 2,220,839, granted November 5, 1940.

2

In the aforesaid patent it is pointed out that if a uniform stream of charged particles is caused to traverse a region which is subjected to cyclically variable potential gradients, the various elements of the stream will be differently affected as to velocity. That is to say, if the particles are electrons, those electrons which traverse the given region when the gradient in it is positive will be accelerated, while electrons which enter the region during periods of negative gradient will be decelerated. In the event that the potential applied to the said region is of cyclically reversible character, the portion of the electron stream issuing from the region will be characterized by alternate components of high and low velocity, this condition corresponding to so-called "velocity modulation" of the stream.

Brief consideration will show that if a velocity modulated electron stream is permitted to continue along a fixed path, a regrouping of the electrons will occur as a result of the tendency of the faster electrons to catch up with the slower ones. Consequently, after an appreciable interval of time, the stream will assume a "charge density modulated" character in the sense that it will possess an unequal space distribution of electrons.

The present invention makes use of the phenomena described above in that it employs the expedient of successively producing velocity modulation of an electron stream and thereafter converting the velocity modulation into charge density modulation for the accomplishment of certain desired results.

35 Referring particularly to Fig. 1, there is shown an exemplary embodiment of the invention in the form of an elongated evacuated discharge tube terminating at one end in a bulbous glass portion 10. The part 10 includes a reentrant stem 11 which terminates in a press 12 for supporting a filamentary cathode 14 and a pair of aligned conductive (metallic) cylinders 16 and 17. The former of the two cylinders serves primarily to confine the electrons released from the cathode 14 to a concentrated beam and to this end may be either connected directly to the cathode as shown or maintained a few volts negative or positive with respect to it. The cylinder 17 acts to accelerate the electron stream and is accordingly biased to a suitable positive potential, say several hundred volts, with respect to the cathode.

In addition to the bulbous part 10, the tube envelope includes an elongated hollow conductive structure which is designated as a whole by the numeral 20 and which is joined to the part 10 by means of a hermetic seal indicated at 21. A conically shaped metallic member 22 covers the seal between the glass and metal parts of the tube and serves to shield it from the effect of the

high potentials which may be developed within the tube during its use.

The tube part 20 is of continuously conductive character, being preferably constituted of an assembly of copper or brass rings, and is characterized internally by a series of recurrent discontinuities. In the particular embodiment shown in Fig. 1 these discontinuities comprise a number of perimetricaly complete (e. g. annular) wall parts 25 to 27 which effectively subdivide the main body of the tube into a series of identical sections. These wall parts define between them a succession of gaps 30 to 33 which are successively traversed by the stream of charged particles projected from the cathode 14. After traversing the gaps, the stream is collected by a metallic end wall 35 which closes the extremity of the tube.

In the operation of the tube, the structure 20 may be maintained at ground potential and the cathode at one to several thousand volts below ground. This may be accomplished by the use of a D. C. voltage source which is illustrated conventionally as a battery 36 and which also serves to bias the electrode 17 to the desired potential. The electron stream developed by the coaction of the various tube elements may, if desired, be maintained in focused condition by the provision of a direct current excited magnetic focusing coil 37.

In order to understand the practical operation of a structure of the character outlined in the foregoing, it should be noted that the part 20 may be viewed in two aspects. In the first it comprises a series of electrode elements for influencing the electron stream traversing it. In the second it may be considered as a unitary resonant system adapted to be maintained in continuous oscillation by the reaction of the electron stream. The relative dimensions of the various parts of the structure should be such as to permit it to function satisfactorily in both of these capacities.

In order further to clarify the matters just referred to, it will first be assumed (subject to later justification) that the structure 20 may be maintained in a condition of sustained oscillation (resonance) such that cyclically reversible potential gradients appear across the gaps 30 to 33 inclusive. It is assumed further that the circumstances of operation are such as to cause the gradients existing in the various gaps to be of similar magnitude and to have a common direction at any given time. (It will be pointed out at a later point that this represents only one of several equally possible modes of operation.) Under these circumstances it is clear that the electron stream traversing the various gaps necessarily undergoes some degree of velocity modulation. Moreover, such modulation is most pronounced if the electron transit time between corresponding points in two adjacent gaps corresponds at least approximately to an integral number of complete cycles of potential variation at the operating frequency of the apparatus.

With the above specified conditions fulfilled, it is apparent that electrons which reach the first gap 30 in such time phase as to be accelerated by the potential gradients existing across the gap will be still further accelerated as they traverse the various subsequent gaps. Conversely, electrons which are decelerated at the first gap will be repeatedly decelerated at the remaining gaps. The net result will be that as the electron stream passes longitudinally through the structure 20 it will develop significant velocity differences from point to point and will, in its more advanced por-

tions, become charge density modulated as the faster electrons overtake and become grouped with the slower electrons.

Under proper circumstances, the charge groups thus produced in the stream may be expected to release energy to the resonant structure in such fashion as to maintain it in continuous oscillation. In my prior Patent 2,222,902, it has been shown in connection with a system which, from this standpoint, is analogous to that here being considered that the maintenance of sustained oscillations requires that the average electron transit time between successive gaps shall depart somewhat from the value previously assumed herein, that is, from equivalence to an integral number of complete potential cycles at the operating frequency. The preferred amount of such departure is a function of the number of gaps employed in the system as a whole, and is indicated in the following table, in which θ_b represents the part of a cycle (one complete cycle being equal to 360 degrees) which is required for the transit of an electron from a given point in one gap to a corresponding point in the next succeeding gap.

Table

Number of gaps	θ_b	Degrees	
		2	3
2		270	
3		306.4	
4		322	
5		329.4	
6		334.7	
7		338.4	
8		341.2	

The significance of the foregoing table may be summarized by saying that most effective mutual reaction of the electron stream with the resonant structure 20 will occur when the longitudinal dimensions of the various structural parts are so correlated to the stream velocity and to the desired operating frequency as to bring about a value of θ_b corresponding to the values indicated in the table. It should be noted in this connection that no change in operation will occur if for any selected number of gaps the value of θ_b given in the table is increased by 360° or by some integral multiple of that angle. Thus, if a six-gap system is to be used and design considerations make it desirable to employ an electrode length greater than that which would correspond to 335°, equivalent results may be obtained by using 335° plus 360°, or 695°. It will be understood from a consideration of the table that in every case the average electron transit time from gap to gap will be on the order of the time consumed by an integral number of complete cycles of potential variation (at the desired operating frequency of the apparatus), but will depart therefrom by a fraction of a quarter-cycle of such variation.

The operation of the apparatus as so far described may be summarized by saying that the electron stream projected from the cathode 14 is modulated as it traverses the initial gaps in the resonant structure; that this modulation is effectively amplified by the occurrence of electron-grouping effects as the stream progresses longitudinally of the structure, and that a portion of the energy of the modulated stream is released to the resonant structure at the various gaps subsequent to the first gap to maintain the structure in continuous oscillation. On this latter point it is assumed that sufficient mutual

space coupling exists between the various sections of the resonant chamber to assure that the forced oscillation of the sections last traversed by the electron stream shall be communicated to the sections first traversed by the stream so as to maintain these also in an oscillatory condition. It is found that such coupling exists to a satisfactory degree provided the various chamber sections are in communication with one another through openings having a diameter which is not less than their axial extent. This condition is obviously fulfilled in the arrangement illustrated in Fig. 1 in which the ratio of the diameter of the openings in the wall parts 25 to 27 to the length of such openings is on the order of 2:1.

Assuming favorable circumstances (including an electron stream of adequate intensity), a sufficient amount of energy may be released from the electron stream to the resonant structure 20 so as not only to supply the losses of the structure and to maintain the same in excited condition, but also to permit abstraction of a portion of the energy for external utilization. Such abstraction may be accomplished in one way, for example, by the provision of an inductive loop 37' which is coupled into the space enclosed by the structure 20 and which connects externally with an appropriate utilization device such as a short-wave antenna 38. With this arrangement the apparatus as a whole is obviously adapted for use as an oscillator for the generation and propagation of high frequency signals.

In order still further to explain the matters referred to in the foregoing, it will be helpful to examine briefly the factors which control the resonant operation of a system such as that formed by the structure 20. This may be done most easily by reference to Fig. 3 which illustrates by way of example the third section of the structure 20 and which shows the extremities of this section as being closed by conductive partitions 40 and 41 extending through the central planes of the wall parts 26 and 27.

As thus modified, the section in question comprises a closed chamber including a cylindrical space B which is surrounded by and merges (at the boundary X) into an annular space A. This chamber, like any confined space bounded by a conducting medium, is electrically resonant at various frequencies determined by the dimensions and configuration of the space.

In order to analyze the properties of the chamber of Fig. 3 in a useful way, one may set up Maxwell's field equations for the enclosed space and solve the equations in a manner consistent with the specified boundary conditions. In an article published in the Journal of Applied Physics for January 1941 at pages 62 to 68 I have shown one procedure by which such an analysis may be carried out. This analysis includes the derivation of equations which permit the resonant frequencies of a chamber of the type in question to be determined if its dimensions are known, and which further allow a missing dimension to be calculated if the remaining dimensions and the desired operating frequency are taken as fixed.

The form of the solution given in the article mentioned above suggests that a structure of the type under consideration may be conveniently viewed as comprising the combination of two radial "transmission lines" (corresponding to the spaces A and B), the former comprising the opposed annular surfaces of the parts 26 and 27 and the latter being made up of the disk-like partitions 40 and 41. The first line is obviously

terminally short circuited by the wall part 20a, and the two lines are joined by the axially extending surfaces 26a and 27a. It may be assumed that from an approximate viewpoint, resonance will occur when the impedance looking into the first mentioned transmission line (the line A) from its inner periphery is equal and opposite to the impedance of the second named transmission line as viewed from the region of its junction with the first line. In another manner of statement, this means that the effective inductance of transmission line A must resonate with the effective capacitance of transmission line B; the lumped circuit analogy of this situation being represented in Fig. 4. In the latter figure, the various circuit elements are numbered to correspond insofar as possible to the equivalent structural elements of Fig. 3. The resulting combination includes inductive components 26' and 27' which are balanced (at resonance) against a capacitive component B'.

Considerations of symmetry indicate that a large number of identical resonant chambers of the character shown in Fig. 3 may be placed end-to-end and the partitions between them removed without modifying the conditions of resonance of the various units. (This, of course, produces the construction of Fig. 1.) For the end section 30 there is some dissymmetry due to the necessity of providing in abutment with this section an open-ended tube 42 through which the electron beam may enter the resonant chamber. (This tube should have a diameter less than about .6 times the operating wave length and a length at least several times its diameter in order to avoid radiation through it of high frequency energy generated within the chamber 20.) The effect of this dissymmetry may be compensated, however, by an end correction in the form of a reentrant annular collar 43 the function of which is to add effective inductance in the end chamber to correct for the reduced capacitance attributable to the presence of the tube 42.

During operation of a structure of the type under consideration, the flow of conduction current will obviously be confined wholly to the walls of the resonant chamber. Moreover, for the most probable condition of operation, it will be wholly unidirectional at any given instant, flowing toward either one end or the other end of the chamber. For either case a compensatory displacement current, flowing in the opposite direction, exists near the axial region of the chamber.

From another point of view the structure of Fig. 1 may be regarded as a modified form of resonant wave guide, analogous to the wave-guiding systems described by G. C. Southworth at pages 284 to 308 of the Bell System Technical Journal for April 1936. In the publication referred to it is pointed out that a continuous conductive tube filled with a dielectric medium may be used for the guided propagation of high frequency electromagnetic waves in spite of the apparent absence of a conductive return circuit of the character usually regarded as necessary to any channelized flow of electrical energy. The waves which may be propagated in this way include, among others, waves having electric force components which are confined to the axial and radial directions and magnetic force components which are wholly azimuthal, such waves being arbitrarily designated as E_0 waves. Under appropriate circumstances E_0 waves of definite frequency may be caused to

exist in a standing wave pattern within a wave guide of given dimensions, this condition being taken to define resonance of the wave guide for the particular frequency involved.

The application to the present invention of the matters stated in the foregoing may be understood by reference to Fig. 5, in which the solid line structure 45 represents a tubular wave guide of dimensions chosen to provide a particular resonant frequency for E_0 waves.

Let it now be assumed that the diameter of the tube is diminished at periodically spaced regions 46 to 48, for example, by inward deformation of the tube wall. Due to the relationship of the magnetic and electric force components in E_0 waves, as defined above, the volume affected by the proposed change is that in which magnetic energy storage is predominant. Consequently, the change reduces the inductance of the system without correspondingly varying its capacitance and thus tends to raise the resonant frequency of the structure of a whole. In order to offset this effect and to provide enough added inductance to restore the original condition of resonance, the diameter of the remaining portions of the tube may be increased as indicated at 49, 50, 51, and 52 so as to provide added volume for magnetic energy storage. With this change the wave guide ought to function essentially as it did in its original condition in so far as resonant operation is concerned.

It will be realized, however, that due to the existence of the gaps 54 to 56 a structure having the configuration indicated by the dotted line will be characterized, when in resonance, by the existence of periodically spaced and sharply defined variations in the axial potential gradient, which variations are not present in the smooth tube 45. In the use of the structure in a system in which an electron stream axially traverses the structure, these variations may be made to produce a significant reaction on the electron stream, and under proper conditions to result in the occurrence of self-sustained oscillations. From this viewpoint then, the dotted line structure of Fig. 5, although derived and described on the basis of wave guide principles, is the functional equivalent of the chamber 29 of Fig. 1.

It may also be noted at this point that any resonant system of the type under consideration is characterized by a theoretically infinite number of modes of resonance. It is, of course, intended that in practical use, a given apparatus shall be restricted to a single preselected mode of resonance by judicious choice of the operating conditions, including appropriate selection of the operating voltage and beam current. On the other hand, some structures may well have a number of modes of operation, all of which are realizable by the use of practically attainable operating conditions. It is, therefore, in no sense a departure from my invention to so modify the operating conditions of a given apparatus having a construction of the type disclosed herein as to procure its operation in a mode of resonance different from that specifically assumed in the foregoing. For example, a resonant structure such as that shown in Fig. 1 and having an even number of gaps may be expected to resonate not only under such circumstances that the potential gradients in the various gaps are at any given time unidirectional (as above explained), but also in an alternative condition such that the gradients in alternate gaps are oppositely directed. This represents a useful condition of oper-

ation within the scope of the present invention provided the electron transit time between successive gaps is made to correspond approximately to an odd number (including unity) of half-cycles of potential variation so that cumulative acceleration and deceleration effects are realized at the various gaps.

In the design of a resonant system of the type under consideration (e. g. in Fig. 1) it is generally expedient to assume a practical dimension for the interior diameter of parts 25, 26, etc.; next, to select a convenient operating voltage; and from this and the desired frequency to compute the longitudinal dimensions of the system. This leaves still undetermined the diameter of the chamber in the regions between the parts 25 to 27, but this may be calculated by the procedure given in the Journal of Applied Physics for January 1941 to which reference has already been made.

With the dimensions of the structure thus determined, one may next compute the losses of the system (mainly resistance losses in the wall parts of the structure) and decide upon a beam current sufficient to provide for these losses and to permit useful power to be taken from the system. Provided the chosen conditions of operation prove to be such as to assure the operation of the system in its desired mode of resonance to the exclusion of other and unwanted modes, the design may be accepted as a practical one.

One advantage of electronic apparatus of the type herein described lies in the fact that all parts of the resonant structure are directly electrically connected and may therefore be maintained at a fixed D. C. potential. This means that the operation of the apparatus will be free from sporadic variations due to wall-charging or the like, irrespective of the number of cascaded sections which are included.

An alternative type of oscillator, shown in Fig. 6, comprises a bulbous glass envelope portion 60 which is joined at its open end to an elongated metal tube 61. A reentrant stem 62 provided in connection with the glass part 60 supports the combination of a cathode 63, a focusing electrode 64 and an accelerating electrode 65, these elements being adapted to project a stream of electrons axially of the envelope. Focusing and energizing means similar to those shown in Fig. 1 may be employed.

The metal tube 1 is closed at its extremity by a transverse metal wall 66 which serves to collect the electrons after their traversal of the tube. The tube further surrounds and supports a series of metallic partition-forming elements which subdivide the enclosed space in a manner analogous to the parts 25 to 27 of Fig. 1. In this case, however, the partition-forming elements 60 comprise a series of abutting rings 68 to 71 of relatively large diameter having smaller coaxial tubular elements 73 to 76 joined thereto by thin imperforate annular webs 78 to 81. A passage for electrons into the sectionalized chamber defined by the elements just referred to is provided through a tubular member 82 which connects with the first section of the chamber.

A system such as that shown in Fig. 6 may be made to operate in much the same manner as the apparatus of Fig. 1. That is to say, assuming proper correlation of the electron velocity with the spacing of the rings and with the desired operating frequency, effective mutual reaction of the electron stream and the structure traversed by it may be expected to occur at the gaps be-

tween the rings 73—76 in such a manner as to produce concurrent modulation of the former and excitation of the latter. The oscillations thus established in the space within the tube 61 may be caused to produce useful external effects by means of a coupling loop 85 which connects with coaxial conductors 86 and 87 extending outwardly through the wall 66.

It is found upon analysis that an annular space such as that bounded by the opposed webs 78 and 79 and the various conductive surfaces which are continuous therewith presents a greater apparent inductance at its inner boundary than does a chamber such as the space A of Fig. 3—assuming like radial dimensions and spacing of partition centers. On the other hand, the apparent capacitance observed at the same boundary—looking toward the central axis of the chamber—is identical for the two structures. Since the inductance of the outer space is variable with the radial dimensions of the partitioning elements, this means that for a given diameter of central opening, the over-all diameter of the chamber required for resonance is less in the Fig. 6 construction than in that of Fig. 1. This permits apparatus embodying the former construction to be made in a relatively more compact form.

Calculation further shows that the internal losses of resonant structures of the type under consideration are also mainly a function of the dimensions of the radially extending parts. Consequently, in situations in which it is important to keep such losses at a low value, it is advantageous to employ the construction of Fig. 6. The optimum design in this connection is believed to be that in which the wall parts 78—81 are made as thin as is reasonably possible—since this permits the radial dimensions of these parts required for resonance to be made a minimum.

In some instances the subdivision of the resonant chamber may advantageously be accomplished by other means than inwardly extending partitions such as are illustrated in Figs. 1-7. One such alternative embodiment is shown in Fig. 8, which illustrates only the resonant structure, the remaining components of the discharge tube being omitted in the interest of simplicity.

In this case the chamber within which oscillations are to be developed is in the form of an elongated conductive cylinder 90 which at one end is joined through a smaller cylinder 91 to a glass envelope, of which only a fragmentary portion 92 is illustrated. It is assumed that the envelope 92 contains means (not shown) for projecting an annular stream of electrons longitudinally of the chamber 90 as indicated by the arrows D. (The electron source employed in this connection may comprise, for example, an arrangement of the type described in application Serial No. 347,744 of Louis Tonks, filed July 26, 1940, Patent No. 2,276,806, dated March 17, 1942 and assigned to the same assignee as the present application.)

Arranged coaxially within the chamber 90 there is provided an elongated conductive shaft 95 having mounted thereon a series of equally spaced conductive cylinders 97—102, the cylinders being mounted on and electrically connected to the shaft by means of imperforate diaphragms as indicated at 103. The cylinder 97 occupies a substantial portion of the cross-section of the entrance tube 91 and projects somewhat into the interior of the chamber 90. (The annular space between the cylindrical parts 97 and 91 is longitudinally subdivided by partitions 104—best

shown in Fig. 9—which serve to prevent undesired propagation of wave energy outwardly through the space during operation of the apparatus.) The remainder of the cylinders serve partially to subdivide the interior of the chamber in a manner analogous to the partitions 25—27 of Fig. 1.

By virtue of this subdivision each of the sections of the chamber may be considered as a separate resonant compartment having, as in the case of the structures previously described, a resonant frequency determined by the dimensions of its component parts. When the structure is in a condition of resonant excitation, cyclically reversible potential gradients directed axially of the chamber may be expected to exist at the gaps which separate the various cylinders. Consequently, as the electron stream passes in proximity to these gaps, its constituent electrons will be variously accelerated and decelerated in such a manner as to produce velocity modulation of the stream. If the resonant structure were excited from an external source, most effective modulation could be produced by making the electron transit time between corresponding points in adjacent gaps equal to an integral number of complete cycles of potential variation at the resonant frequency (or, for certain modes of operation, to an integral number of half cycles at such frequency). However, in order to assure the maintenance of sustained oscillations with the self-excited arrangement shown, the spacing between adjacent gaps should be slightly less than that calculated to give the result just specified. With this condition fulfilled, a portion of the oscillatory energy developed within the chamber 90 may be abstracted for external use by means of an appropriate coupling loop 105. In this instance the loop 105 connects with an antenna 106 which is wholly within the vacuum space, being terminally confined by a glass closure member 107.

Fig. 10 illustrates a construction which combines certain of the features of Figs. 1 and 8. In this case, the resonant system comprises an elongated cylindrical chamber 110 having an axially extending conductive shaft 111 which bears a series of conductive cylinders 113—116 inclusive. Each of the cylinders is surrounded by an annular conductive partition 120—123 which still further increases the degree of subdivision of the chamber. However, the annular passages between the outer surfaces of the members 115—116 and the inner surfaces of the members 120—123 permit an electron stream to be projected longitudinally of the chamber. In the case illustrated, the electron stream comprises a single pencil of electrons E which is injected into the chamber through a tubular opening 128 and which leaves the chamber at its opposite extremity through an aligned opening 129, being intercepted upon its issuance from the chamber by a collecting electrode 130. The electrode 130 is insulating supported with respect to the chamber from an insulating (e. g. glass) wall 131 and is assumed to be maintained at a potential adapted to assure the collection of all the electrons.

Obviously the general considerations which have previously been stated herein as governing the resonant operation of subdivided chambers apply without substantial modification to the arrangement of Fig. 10. That is to say, the electron stream E will, if the dimensions of the system are properly correlated to the stream velocity and to the desired operating frequency, be modulated at the gaps which it first traverses and will release a portion of its energy to the sur-

rounding structure at the gaps which it traverses near the end of its path. The oscillatory energy thus developed within the chamber may be utilized by the provision of a suitable output circuit (not shown).

The various structures which have been described in the foregoing have been illustrated as being of cylindrical character. It is to be understood, however, that this is not an essential attribute of the invention and that other cross-sectional forms may be adopted. For example, Figs. 11 and 12 represent, respectively, a cross-sectional view and a partial longitudinal section of a chamber which, externally viewed, is of square configuration. It comprises a conductive enclosure 140 and a plurality of transverse conductive partitions, of which those shown are numbered 141 and 142. This construction, which in its complete form may be assumed to be generally similar to the tube shown in Fig. 1 (except for its cross-sectional configuration), may be expected to operate in a manner generally analogous to that specified in connection with the former construction, due allowance being made in the calculation of resonant frequency for the different boundary conditions imposed by the shape involved.

Still other and more complex configurations, such as chamber of oblate cross-section, may also be employed.

Furthermore, while the invention has so far been described solely in connection with oscillations adapted for the generation and transmission of high frequency waves, it is by no means limited to this use and may be alternatively employed in the amplification and detection of received signals. Fig. 13, for example, schematically illustrates an amplifier embodying a resonant system of the general character of that illustrated in Fig. 1.

The structure referred to comprises an elongated glass shaft portion 150 which encloses a cathode 151, a focusing electrode 152 and a series of aligned cylindrical electrodes 153-155, inclusive. These latter electrodes are maintained at increasingly positive potentials by appropriate connection to a battery 157.

The central electrode 154 is subjected to a high frequency signal which may be derived, for example, from an antenna 159 and which is applied to the electrode through an appropriate circuit, illustrated diagrammatically as comprising the parallel combination of an inductance 160 and a capacitance 161. As a result of the potential variations of the electrode 154, the electron stream proceeding from the cathode 151 will obviously become velocity modulated as it traverses the gaps between this electrode and the electrodes 153 and 155. With appropriate dimensions of the electrode 154 the modulating effects may be made cumulative at the two gaps.

After passage through the electrode 155, the modulated electron stream is projected into a chamber 164 which is similar in structural form to the chamber 20 of Fig. 1. However, the longitudinal dimensions of the various subdivisions of the chamber 164 are preferably made such as to assure that the electron transit time between corresponding points in adjacent sections corresponds as nearly as possible to an integral number of complete cycles of potential variation at the resonant frequency of the chamber. Under these circumstances, and for reasons previously given herein, there will be little tendency for the chamber to break into self-sustained oscillations

as a result of its mutual reaction with the electron stream—except in so far as the stream may be modulated prior to its entrance into the chamber. Such excitation of the chamber 164 as occurs will be a result of the prior modulation of the electron stream by the electrode 154 and will be proportional to the amplitude of such modulation. However, the strength of the waves developed within the chamber 164 as a result of its excitation by the modulated stream may be very much greater than the strength of the received signal wave, thereby permitting amplification effects to be obtained. The amplified energy developed within the chamber may be effectively utilized by the provision of a coupling loop 166 provided at an appropriate location within the chamber and having an external connection 167 adapted for coupling to a suitable utilization device such as a detector (not shown).

Although the invention has been exemplified by reference to devices operated with a pure electron discharge, it should be understood that the principles set forth are applicable in their general aspects to other types of charged particles. For example, results generally similar to those described may be obtained by the use of a positive ion stream cooperating with structures of the character referred to herein.

Moreover, while the invention has been described in connection with particular structures and in particular modes of use, it will be understood that numerous modifications may be made by those skilled in the art without actually departing from the invention. I, therefore, aim in the appended claims to cover all such equivalent variations as come within the true spirit and scope of the foregoing disclosure.

What I claim as new and desire to secure by Letters Patent of the United States, is:

1. In combination, an elongated hollow conductive structure, a succession of discontinuities within the structure subdividing the enclosed space into a series of space-resonant sections which are individually resonant at a common frequency, all the bounding surfaces of the various sections being electrically interconnected by low resistance paths and there being a passageway extending longitudinally of the structure for spatially interconnecting the sections, and means for projecting charges through the said passageway to produce energy conversion effects by mutual reaction of the said charges and the said resonant sections.

2. In combination, an elongated hollow conductive structure, a succession of conductive elements positioned at regularly spaced intervals within the structure and having extensions in a direction transverse to its longitudinal axis for subdividing it into a series of space-resonant sections, all the bounding surfaces of the various sections being electrically interconnected by low resistance paths and there being a passageway extending longitudinally of the structure for spatially interconnecting the said sections, and means for projecting charges through the said passageway to produce energy conversion effects by mutual reaction of the said charges and the said resonant sections.

3. In combination, a hollow continuously conductive structure providing an elongated chamber, a plurality of conductive partitioning elements positioned at regularly spaced intervals along the length of the chamber and providing gaps between the elements, the said elements subdividing the chamber into a plurality of sim-

ilar space-resonant sections each of which is individually resonant at the same frequency, and means for projecting charged particles successively through the various sections and across the said gaps to produce energy conversion effects by virtue of the mutual reaction of the said resonant sections and the said particles.

4. In combination, an elongated hollow conductive structure having inwardly projecting conductive wall parts at regularly spaced intervals along the length of its interior surface, said wall parts effectively dividing the space enclosed by the structure into a series of similar space-resonant sections each of which is individually resonant at the same frequency, and means for projecting a stream of charged particles successively through the various sections to produce energy conversion effects by the mutual reaction of the said structure and the said stream.

5. A high frequency oscillator comprising means defining an elongated chamber of continuously conductive character, a succession of electrically connected conductive elements providing recurrent discontinuities within the chamber along its length, said elements effectively dividing the chamber into a plurality of space-resonant sections each of which is individually resonant at the same frequency, the various sections being connected by a passageway extending longitudinally of the chamber, means for projecting moving charges through the passageway to generate electromagnetic waves within the chamber by mutual reaction of the said charges and the said resonant sections, and means for abstracting a portion of the wave energy thereby developed for utilization outside the said chamber.

6. A high frequency oscillator comprising an elongated hollow conductive structure having inwardly projecting conductive wall parts at regularly spaced intervals along the length of its interior surface, said wall parts effectively dividing the space enclosed by the structure into a series of similar space-resonant sections each of which is individually resonant at a common frequency, means for projecting a stream of charged particles successively through the various sections to generate high frequency electromagnetic waves within the structure as a result of the mutual reaction of the structure and the said stream, and means for abstracting a portion of the resultant wave energy for utilization outside the structure.

7. High frequency apparatus comprising a continuously conductive structure which defines an elongated chamber, a succession of conductive elements providing recurrent discontinuities within the chamber along its length, said elements effectively dividing the chamber into a plurality of space-resonant sections each of which is individually resonant at the same frequency, the various sections being connected by a passageway extending longitudinally of the chamber, and there being an opening in the said chamber of such constricted dimensions as to inhibit the propagation through the opening of electromagnetic waves of the said frequency, means including a cathode outside the chamber for projecting electrons longitudinally of the chamber through the said opening and passageway, thereby to maintain the chamber as a whole in a state of resonant excitation by the generation within it of electromagnetic waves of the said frequency, and means for abstracting at least a portion of

the resultant wave energy for use external to the said chamber.

8. In combination, an elongated hollow conductive structure, a series of axially aligned tubular conductive elements positioned within the structure and extending longitudinally thereof, the said elements being mutually spaced to provide gaps between their adjacent extremities, conductive wall parts extending between the said elements and the lateral walls of the said structure for supporting the elements and for connecting them electrically to the structure, said wall parts dividing the structure into a series of similar resonant cavities which are connected through the axial openings in the said tubular elements, and means for projecting charged particles successively through the said tubular elements and across the said gaps so as to produce energy conversion effects by the mutual reaction of the particles and the said resonant cavities.

9. High frequency apparatus including a hollow conductive structure defining an elongated chamber, a series of axially aligned electrically connected conductive bodies supported centrally within the said structure and extending longitudinally thereof, the said bodies being mutually spaced to provide gaps between them and serving to divide the said chamber into a plurality of similar space-resonant sections, each resonant at the same frequency, and means to project charged particles longitudinally of the chamber in proximity to the said conductive bodies, thereby to produce energy conversion effects resulting in the generation within the structure of high frequency electromagnetic waves.

10. High frequency apparatus including a hollow conductive structure defining an elongated chamber, a series of axially aligned cylindrical conductive bodies supported centrally within the said structure and extending longitudinally thereof, the said bodies being mutually spaced to provide gaps between them and serving to divide the said chamber into a plurality of similar sections, each resonant at the same frequency, conductive means materially smaller in diameter than the said cylindrical bodies for directly connecting the various bodies along a line which is coincident with their common axis, and means to project charged particles longitudinally of the chamber in proximity to the said conductive bodies, thereby to maintain the chamber in a condition of resonant excitation by virtue of the mutual reaction of the charged particles and the various conductive components of the apparatus.

11. High frequency apparatus comprising a hollow conductive structure defining an elongated chamber and having inwardly projecting conductive wall parts at regularly spaced intervals along the length of its interior surface, a series of electrically connected conductive bodies supported centrally within the chamber, said bodies corresponding in number and axial distribution to the said wall parts and serving in cooperation with the wall parts to divide the chamber into a series of similar space-resonant sections which are individually resonant at the same frequency and which are connected through spaces existing between the respective bodies and the adjacent wall parts, and means for projecting charged particles successively through the various sections, thereby to maintain the said structure in a state of resonant excitation.

WILLIAM C. HAHN.
